Primary Examiner — Patricia A Palasik*(74) Attorney, Agent, or Firm* — Stoel Rives LLP(57) **CLAIM**

The ornamental design for a mobile robot, as shown and described.

DESCRIPTION

FIG. 1 is a perspective view of the design for a mobile robot; FIG. 2 is a front view thereof, the rear view being identical thereto;

FIG. 3 is a left view thereof, the right view being identical thereto;

FIG. 4 is a top view thereof; and,

FIG. 5 is a bottom view thereof.

The broken lines shown in the figures depict portions of the mobile robot that form no part of the claimed design.

1 Claim, 3 Drawing Sheets(56)
